CLAIM

The ornamental design for a flexible razor cartridge design, as shown and described.

DESCRIPTION

FIG. 1 is a top front perspective view of a flexible razor cartridge showing my new design;

FIG. 2 is a right side elevational view thereof, the side opposite being a mirror image of the side shown;

FIG. 3 is a top plan view thereof;

FIG. 4 is a front elevational view thereof;

FIG. 5 is a rear elevational view thereof;

FIG. 6 is a bottom plan view thereof;

FIG. 7 is a top front perspective view of a second modified embodiment; and,

FIG. 8 is a top plan view thereof.

The undisclosed sides of the embodiment represented in FIGS. 7 and 8 are identical to the first disclosed embodiment.
